CUTTER BLADE HOLDER**Gustave O. Matter, 3112 NE. 46th Ave., Portland, Oreg.****Continuation of application Ser. No. 349,390, Apr. 17, 1953. This application Oct. 18, 1957, Ser. No. 694,472****10 Claims. (Cl. 30—293)**

My invention is a device for holding a cutter blade, as for example a safety razor blade, when used to cut material such as the edge of an envelope, or magazine wrapper, or to cut cardboard or cloth and the like, or when used as a scraper to remove excess paint from window glass and the like, and is a continuation of my co-pending application Serial Number 349,390, now abandoned.

An object of my invention is a holder for a cutter blade which permits opening an envelope quickly and without damaging its contents.

Another object is a holder for a cutter blade which can be used to cut open a magazine wrapper without damage to the magazine.

Another object is a cutter blade holder which limits the amount cut from the edge of the material being cut.

Another object is a cutter blade holder which limits the depth of cut into the material being cut.

Another object is a cutter blade holder wherein the cutter blade will not become clogged by particles from the material being cut.

Another object is a cutter blade which permits changing the position of the material being cut in relation to the cutting edge of the cutter blade without re-positioning the cutter blade in the holder.

Referring to the drawings, in which like characters of reference indicate corresponding parts throughout the several views:

Fig. I is a front elevation of the holder with a cutter blade in position as when opening an envelope by cutting a narrow strip from an edge of the envelope.

Fig. II is a right hand elevation of Fig. I.

Fig. III is a rear elevation of the holder shown in Fig. I.

Fig. IV is a section taken on line IV—IV of Fig. III.

Fig. V is a section taken on line V—V of Fig. I.

Fig. VI is a fragmentary view of an envelope in dotted outline, together with portions of the holder and cutter blade indicating the manner of operation when opening an envelope.

Fig. VII is a front elevation of the holder with a cutter blade in position as when used as a scraper.

Fig. VIII is a front elevation of the holder with a cutter blade in position to cut material to a depth not exceeding the distance the blade projects from the holder.

Fig. IX is similar to Fig. VIII but showing the blade positioned to use either of two cutting edges.

Fig. X is similar to Fig. I but showing, in dotted outline, a magazine envelope or wrapper being cut open.

Fig. XI is a fragmentary view of a magazine and wrapper, in dotted outline, together with portions of the holder and cutter blade in section indicating the manner of operation when opening a magazine wrapper or envelope.

Fig. XII is similar to Fig. X but showing the envelope supporting member swung out of normal position to permit the blade to cut a magazine wrapper or envelope which is thicker than the space between the depending leg and the lower edge portion.

Fig. XIII is a view similar to Fig. I showing the envelope supporting member in its down position thereby

guiding the material to be cut, such as an envelope, shown in dotted outline, to the lower exposed portion of the cutting edge of the blade.

Fig. XIV is a view similar to Fig. XIII but showing the envelope supporting member in up position and thereby guiding the envelope or the like, shown in dotted outline, to the upper exposed portion of the cutting edge of the blade.

Fig. XV is an enlarged section taken on line XV—XV of Fig. I showing the relative position of the blade to the lower edge portion and to the inner edge of the horizontal leg of the support member.

Referring to the numerals on the drawings, the holder comprises a plate having a main body portion 1 and a lower edge portion 3 joined with the main body portion by means of the offset portion 2 so as to present the stepped inner surfaces as is shown most clearly in Fig. V. The holder also includes a cover plate 5 and a cutter blade 4 which is sandwiched between the cover plate and the main body portion. An envelope supporting member is secured to the lower edge portion 3 and such member includes a horizontal leg 12 which extends substantially perpendicularly to the inner surface of the lower edge portion 3 and a depending leg 7 which extends generally in parallel relationship to the inner surface of the lower edge portion 3.

The greater portion of the envelope supporting member is of L-shaped configuration in cross section but a portion thereof is of U-shaped configuration by virtue of the depending leg member 7' as is shown most clearly in Figs. II and IV and this leg 7' is abutted in face-to-face relation with the inner surface of the lower edge portion 3 and is pivoted thereto as by means of a rivet 8 or similar member and also carries a clamping screw 9, the stem of which projects through an arcuate slot 10 opening upon the lower edge of the portion 3 so as to permit adjustability between the envelope supporting member and the cutter blade 4.

In use, the cutter blade 4 is disposed substantially in the position as is shown in Fig. I wherein the cutting edge thereof angles downwardly so that at least a portion extends between the inner free edge of the horizontal leg 12 and the opposed inner surface of the lower edge portion 3. When in this position, an envelope as indicated by the dotted lines 11, may be engaged upon the upper surface of the horizontal leg 12 and slit lengthwise as is shown most clearly in Fig. VI to open the envelope while removing only a small marginal strip 14 thereof.

For the purpose of securing the cutter blade 4 in sandwiched relationship between the cover plate 5 and the main body portion 1, a clamping screw or bolt 6 is provided as will be readily apparent. Both the cutter blade and the main body portion 1 are provided with a plurality of apertures through which the clamping bolts 6 may be engaged to hold the cutter blade 4 in various positions as is illustrated in Figs. I, VII, VIII and IX for performing various cutting operations as will be readily apparent.

The slot 10 is of sufficient length so that the envelope supporting member may be swung to an adjusted position such as is illustrated in Fig. X, the purpose of this construction being to permit slight adjustment of the envelope supporting member with relation to the cutter blade so as to expose a different and sharper portion of the blade after the holder has been in use.

It is to be noted that a slight spacing as indicated by the reference character 13 is provided between the cutter blade 4 and the inner surface of the lower edge portion 3, this spacing determining the width of the strip slit from the envelope, whereas it is also desirable to have slight spacing as indicated at 15 in Fig. XV between the

cutter blade 4 and the inner free edge of the horizontal leg 12 so as to prevent clogging.

To remove a wrapper or envelope from a magazine, the holder with its cutter blade 4 is adjusted to the position as shown in Figs. X and XI and the edge of the magazine 16, shown in dotted outline, is held in the space 17 between the inner surface of the depending leg 7 and the opposed inner surface of the lower edge portion 3, see particularly Fig. XI. The holder with its blade 4 is then drawn along the edge of the magazine wrapper 16 to cut a slit in the wrapper. Should the magazine be thicker than the spacing 17, such a magazine 18, as is shown in Fig. XII is operated upon with the envelope supporting member swung away from and out of covered relationship to the cutter blade.

To cut flat material, the blade can be projected from the holder as shown in Figs. VIII and IX and the maximum depth of the cut will be determined by the amount of the blade which is exposed.

When used as a scraper to remove unwanted paint or the like from the surface, the blade 4 can be positioned in the holder as is shown in Fig. VII.

While the specification sets forth in detail the present and preferred construction of the device, deviations from the construction shown may be resorted to without departing from the spirit of the invention as defined in the appended claims.

In view of the foregoing description, taken in conjunction with the accompanying drawings, it is deemed that a clear understanding of the invention will be apparent to those skilled in the art. Therefore, a more detailed description is accordingly thought unnecessary.

Having described the invention, what is claimed as new is:

1. An envelope opener comprising a plate having a main body portion and an offset lower edge portion defining stepped, substantially parallel inner surfaces, an L-shaped envelope supporting member secured to said plate and being positioned substantially parallel to and coextensive with said lower edge portion, one leg of said envelope supporting member being parallel to but spaced from said inner surface of the lower edge portion and the other leg extending from the first leg perpendicularly toward said inner surface of the lower edge portion, said other leg having a portion with a free edge and being parallel and spaced outwardly from said inner surface of said lower edge portion of said plate, and a cutter blade fixed in face-to-face relation to the inner surface of said main body portion with a portion of its cutting edge projecting beyond the juncture of said main body and offset lower edge portions and extending between said plate and said envelope supporting member and in spaced relation to that portion of said free edge of said other leg that is spaced from the inner surface of said lower edge portion.

2. The opener as defined in and by claim 1 wherein said envelope supporting member is pivotally mounted at one end thereof to said inner face of the lower edge portion of the plate.

3. The opener as defined in and by claim 2 including means for holding said supporting member in adjusted positions relative to the cutting edge of the cutter blade.

4. The opener as defined in and by claim 3 wherein the last mentioned means includes a clamping screw operating through a slot in said lower edge portion of the plate and clampingly engaging said envelope supporting member upon said inner surface of the lower edge portion of the plate.

5. A cutter blade holder comprising a plate having a main body portion and an offset lower edge portion defining stepped, substantially parallel inner surfaces, an envelope supporting member secured to said plate and being positioned substantially parallel to and coextensive with said lower edge portion, said envelope supporting member having a portion offset from said plate and including a horizontal leg extending substantially perpen-

dicularly toward said inner surface of the lower edge portion and terminating short thereof to present an inner free edge having a portion substantially parallel to and spaced outwardly from said inner surface of the main body portion of said plate, and a cutter blade fixed in face to face relation to the inner face of said main body portion with a portion of its cutting edge projecting beyond the juncture of said main body and said offset lower edge portions and extending between said plate and said envelope supporting member and in spaced relation to that portion of said free edge of said horizontal leg that is spaced from the inner surface of said lower edge portion, the upper surface of said horizontal leg being spaced a substantial distance from said juncture between the main body and the offset lower edge portion and by distance materially greater than the thickness of an envelope to be opened and the region between the inner surfaces of said cutting blade and the opposed inner surface of said lower edge portion being free and unobstructed whereby the strip slit from an envelope being opened is unimpeded and is free from impingement upon or against obstructions so as to permit the same to be entirely free and independent to prevent clogging of said cutting blade.

6. A cutter blade holder comprising a plate having a main body portion and an offset lower edge portion defining stepped, substantially parallel inner surfaces, an envelope supporting member secured on said plate and being positioned substantially parallel to and coextensive with said lower edge portion, said envelope supporting member having a portion offset from said plate and including a horizontal leg extending substantially perpendicularly toward said inner surface of the lower edge portion and terminating short thereof to present an inner free edge having a portion substantially parallel to and spaced outwardly from said inner surface of the main body portion of said plate, and a cutter blade fixed in face to face relation to the inner face of said main body portion with a portion of its cutting edge projecting beyond the juncture of said main body and said offset lower edge portions and extending between said plate and said envelope supporting member and in spaced relation to that portion of said free edge of said horizontal leg that is spaced from the inner surface of said lower edge portion, said supporting member being pivotally mounted at one end thereof to said inner surface of the lower edge portion of the plate.

7. The cutter blade holder as defined in and by claim 6 including means for holding said supporting member in adjusted position relative to the cutting edge of said cutter blade.

8. The cutter blade holder as defined in and by claim 7 wherein the last mentioned means includes a clamping screw operating through a slot in said lower edge portion of the plate and clampingly engaging said envelope supporting member upon said inner surface of the lower edge portion of the plate.

9. A cutter blade holder comprising a plate having a main body portion and an offset lower edge portion defining stepped, substantially parallel inner surfaces, an envelope supporting member secured on said plate and being positioned substantially parallel to and coextensive with said lower edge portion, said envelope supporting member having a portion offset from said plate and including a horizontal leg extending substantially perpendicularly toward said inner surface of the lower edge portion and terminating short thereof to present an inner free edge having a portion substantially parallel to and spaced outwardly from said inner surface of the main body portion of said plate, and a cutter blade fixed in face to face relation to the inner face of said main body portion with a portion of its cutting edge projecting beyond the juncture of said main body and said offset lower edge portions and extending between said plate and said envelope supporting member and in spaced relation to that portion of said free edge of said horizontal leg that

is spaced from the inner surface of said lower edge portion, said horizontal leg of the envelope supporting member being provided with a leg depending from the outer edge of said horizontal leg, the depending leg being parallel to but spaced from said inner surface of the lower edge portion.

10. A cutter blade holder comprising a plate having a main body portion and an offset lower edge portion defining stepped, substantially parallel inner surfaces, a cutter blade fixed to the inner surface of said main body portion and having a portion of its cutting edge extending beyond the juncture between said main body portion and said offset lower edge portion, and a support element fixed to said holder having a face extending substantially at right angles to said cutter blade and positioned on the 15 side thereof opposite said offset lower edge portion to

5 define a shield exposing only a predetermined depth of said cutting edge, said support element being pivotally fixed to said holder for movement to an out of the way position exposing the total depth of said cutting edge which extends beyond said juncture between the main body portion and lower edge portion of the holder.
